US00D820292S

(12) **United States Design Patent** (10) Patent No.: **US D820,292 S**
Mander et al. (45) Date of Patent: **** Jun. 12, 2018**

(54) **DISPLAY SCREEN OR PORTION THEREOF
WITH GRAPHICAL USER INTERFACE**

(71) Applicant: **General Electric Company**, Schenectady, NY (US)

(72) Inventors: **Amanda Ropa Mander**, Seattle, WA (US); **Michelle Ensey**, Seattle, WA (US); **Chelsey Lewis**, Waukesha, WI (US); **Donald Sepulveda**, Humble, TX (US)

(73) Assignee: **General Electric Company**, Schenectady, NY (US)

(**) Term: **15 Years**

(21) Appl. No.: **29/577,832**

(22) Filed: **Sep. 15, 2016**

(51) LOC (11) Cl. **14-04**

(52) U.S. Cl.

USPC **D14/486**

(58) **Field of Classification Search**

(74) Attorney, Agent, or Firm — Hanley, Flight and Zimmerman, LLC

(57) **CLAIM**

The ornamental design for a display screen or portion thereof with a graphical user interface, as shown and described.

DESCRIPTION

A portion of the disclosure of this patent document contains material which a claim for copyright is made. The copyright owner has no objection to the facsimile reproduction by anyone of the patent document or the patent disclosure, as it appears in the U.S. Patent and Trademark Office patent file or records, but reserves all other copyrights whatsoever.

The sole FIGURE is a front view of a display screen or portion thereof with graphical user interface.

The outer broken line showing a display screen or portion thereof and the features shown in inner broken lines form no part of the claimed design.

1 Claim, 1 Drawing Sheet
